UNITED STATES PATENT OFFICE.

ROBERT H. COLLINGHAM, OF RUGBY, ENGLAND, ASSIGNOR TO GENERAL ELECTRIC COMPANY, A CORPORATION OF NEW YORK.

REGULATING MEANS FOR COMPRESSORS, BLOWERS, OR THE LIKE.

Application filed April 7, 1921. Serial No. 459,392.

To all whom it may concern:

Be it known that I, ROBERT HUGH COLLINGHAM, a subject of the King of Great Britain, residing at Rugby, in the county of 5 Warwickshire, England, have invented certain new and useful Improvements in Regulating Means for Compressors, Blowers, or the like, of which the following is a specification.

10 The present invention relates to air or gas compressors, blowers, or the like, driven by turbines, reciprocating engines or other form of prime mover and delivering air to receivers or reservoirs from whence it is drawn 15 to supply air or gas consuming devices.

In such compressors, it is desirable that the power supplied for driving when no air or gas is being delivered should be reduced to a minimum. As no air or gas may be 20 required by consuming devices for a considerable period it would be uneconomical to blow air or gas off to the atmosphere at a pressure, merely to keep the turbo-compressor operating above the breakdown speed, or 25 to blow it off through a safety valve at no load in the case of a reciprocating engine driven compressor.

The object of the present invention is to 30 provide an improved structure and arrangement which operates automatically to reduce to a minimum the power required to operate a blower, compressor, or the like on no load, and for a consideration of what I believe to be novel and my invention, attention is 35 directed to the accompanying description and the claims appended thereto.

In the drawing, which illustrates one form of apparatus for carrying out my invention, Fig. 1 is a sectional elevation of a part of 40 the apparatus; Fig. 2 is a sectional plan view taken on line 2—2 of Fig. 1, the figure being on a smaller scale than Fig. 1, and showing certain additional parts; Fig. 3 is a sectional plan view taken on line 3—3 Fig. 45 1, also on a reduced scale; Fig. 4 is a view of the lower part of the apparatus showing a link and lever mechanism, and Fig. 5 is a diagrammatic view of the complete apparatus shown in Figs. 1 to 4 inclusive.

50 Referring to the drawing, particularly Figs. 1 to 4 inclusive, 10 indicates the inlet to a compressor such as a centrifugal compressor for example. Surrounding the mouth of inlet conduit 10 is a flange 11 to 55 which is fastened a frame 12 by means of

bolts 13 which pass through flange 11 and an abutting flange 14 on frame 12. Between flange 11 and the nuts on bolts 13 are springs 15 whereby frame 12 is held in yielding engagement with the end of the inlet conduit 10. Extending longitudinally of frame 12 is a shaft 16 on which is fixed a valve 17 adapted to close the inlet conduit 10 of the compressor. Shaft 16 is pivotally mounted in the end walls of frame 12, and on its outer ends, which project beyond such walls, are fixed arms 18 which are connected by links 19 and arms 20 to a shaft 21 which extends the length of frame 12 and is carried in suitable bearings 22 as shown in Fig. 2. 65 Formed integral with one of the arms 20 is a second arm 23 which extends at a right angle to arm 20 and is connected at its outer end by a link 24 to a rod 25. Arms 20 and 23 form in substance a bell crank lever as 70 best shown in Fig. 4. Hung on the lower end of rod 25 is a weight 26 and on the upper end of rod 25 is a piston 27 which moves in a cylinder 28 provided with a lining member 29. The arrangement is such that when piston 27 is in its upper position as shown in Fig. 1, that is, at the top of cylinder 28, valve 17 is closed, while when said piston is at the lower end of cylinder 28 valve 17 is open. Normally the piston is at the lower 75 end of cylinder 28 so valve 17 is open, weight 26 serving to bias the parts to this position. Cylinder 28 is supported by a post 30 and fastened to the side of post 30 is a bracket 31 which carries a valve casing 32, 80 the upper portion of which opens into a cylinder 33. In valve casing 32 is a valve 34 adapted to move to opposite sides of a valve chamber 35. Connected to valve chamber 35 is a conduit 36 which leads to the 85 lower end of cylinder 28. The opening through which conduit 36 connects with cylinder 28 is indicated at 37 in Fig. 1 and its connection with valve chamber 35 is indicated at 38. Connected to valve casing 32 at a point below valve chamber 35 is a conduit 39 which leads to the receiver or reservoir into which the compressor discharges. The opening through which conduit 39 connects with valve casing 32 is indicated at 40 in Fig. 1. It will thus be seen that when valve 34 is in raised position as shown in Fig. 1, the lower end of cylinder 28 is connected by way of conduit 36, valve casing 32, and conduit 39 to the receiver 100 105 110

on the discharge side of the compressor. When valve 34 is in its lowered or down position, the upper end of the valve moves down beyond chamber 35 and conduit 36 is then connected directly to atmosphere through a port 41 in the side of valve casting 32. Port 41 is above valve chamber 35 so when valve 34 is in raised position it shuts off connection between conduit 36 and port 10 41 and connects conduit 36 to conduit 39. Valve 34 is provided with a stem 42 which projects into cylinder 33 and connects to a piston 43 located in cylinder 33. On the upper end of piston 43 is a post 44 which supports an adjustable weight 45. In the present instance a portion of weight 45 is shown in the form of a number of discs 46 which can be placed over the upper end of post 44. The weight on post 44 can thus be adjusted 15 by removing or adding discs 46. Piston 43 moving in cylinder 33 forms a dashpot to regulate the closing of valve 34, and also serves as a stop to limit the movements of such valve. 33^a is a needle valve for regulating the flow of air from piston 33. Fastened to the side of post 44 is a catch 47 with which a trigger 48 is adapted to engage to hold valve 34 in raised position. Trigger 48 is pivoted on a shaft 49 and is normally pressed 20 to a position against post 44 by a spring 50, one end of which is attached to trigger 48 and the other of which rests on a web 51 formed integral with cylinder 33. The outer end of web 51 is enlarged to form a cylinder 25 52 in which is located a piston or plunger 53. At 54 is an arm having a bifurcated end which straddles trigger 48 and is pivoted on shaft 49. The free end of arm 54 rests on the upper end of plunger 53. At an 30 intermediate point arm 54 lies above and engages the outer end of trigger 48 and is adapted to move the trigger away from post 44 against the action of spring 50 when the free end of arm 54 is moved downward. 35 Connected to the outer or free end of arm 54 is a stirrup 55 on the lower end of which is hung an adjustable weight 56 which may be of the same general character as weight 45. By removing or adding discs 57 the 40 weight may be adjusted.

As will be clear, weight 56 tends to pull the free or outer end of arm 54 downwardly so as to move trigger 48 away from post 44 and when moved downwardly plunger 53 will be moved downwardly in cylinder 52. The lower end of cylinder 52 is connected by a pipe 58 to the receiver on the discharge side of the compressor. Upward movement of arm 54 is limited by an adjustable stop 45 59 carried by a U-shaped strap 60.

The apparatus shown in Figs. 1 to 4 inclusive is shown in a more or less diagrammatic manner in Fig. 5 as assembled in connection with a centrifugal compressor and receiver. In Fig. 5 the reference numerals

used in connection with Figs. 1 to 4 are applied to corresponding parts. Referring particularly to Fig. 5, 61 indicates a centrifugal compressor having an inlet conduit 10 and a discharge conduit 62 which leads 70 to a receiver 63.

The operation of the device will now be described with particular reference to Fig. 5. The apparatus is adjusted to operate between fixed upper and lower limits by adjusting the counterbalance weights 45 and 56, the former controlling the higher limit and the latter the lower limit of pressure. Assume that the compressor is working normally, supplying air or gas to the receiver from which it is being drawn by the consuming device. Under these circumstances valve 17 will be fully open, piston 27 being at the bottom of cylinder 28 and held there by weight 26. Valve 34 will be held in its lowermost position by weight 45, conduit 36 being connected to atmosphere through port 41. Piston 43 will be at the bottom of cylinder 33. Trigger 48 will be held out of engagement with post 44 by weight 56 acting on the outer end of arm 54, the receiver pressure being below the lower limit for which weight 56 is adjusted.

If now the demand for air or gas cease the receiver pressure will immediately commence to rise. This pressure will be transmitted through pipe 58 to plunger 53 and as soon as the pressure reaches a value above the lower limit, plunger 53 will rise lifting arm 54 free of trigger 48 and permitting spring 50 to hold trigger 48 against post 44. At the same time the receiver pressure is transmitted through pipe 39 to the underside of valve 34, and as soon as the upper limit of pressure is reached, that is the limit for which valve 34 is set by weight 45, the pressure will lift valve 34 thereby placing conduit 36 in communication with the receiver through pipe 39. Pressure from the receiver will then act on the lower side of piston 27 to raise the same and through link 24, arms 23 and 20, links 19 and arms 18, close valve 17. The various parts now assume the positions shown in the figures of the drawing, trigger 48 being now under catch 47. With valve 17 closed the compressor runs in a partial vacuum. In the case of a centrifugal compressor or blower, this means that the prime mover has only to supply sufficient power to rotate the rotor against the rotation losses and the saving of power under these circumstances is very great as compared with a case where air or gas under pressure is blown off to the atmosphere to maintain the set operating above the break-down point.

If now a fresh demand is made on the receiver, the receiver pressure will commence to drop. Valve 34 and weight 45 cannot descend however due to trigger 48 being now 130

in engagement with catch 47. When the pressure in the receiver drops to a point below the predetermined lower limit set by weight 56, such weight pulling down on arm 54 will lower it against the action of the receiver pressure acting on plunger 53 thereby moving trigger 48 from engagement with catch 47. Valve 34 is then free to move downward under the action of weight 45 10 until piston 43 strikes the bottom of cylinder 33. The downward movement of valve 34 is cushioned by piston 43 moving in cylinder 33 which acts as a dashpot. When valve 34 reaches the end of its downward movement 15 conduit 36 is disconnected from pipe 39 and connected to port 41. This permits the pressure under piston 27 to escape to atmosphere, whereupon weight 26 will lower piston 27 and open valve 17. The compressor 61 will 20 then operate in the normal manner with its inlet connected to atmosphere, and the parts are all in a position for a repetition of the cycle of operation just described in case the receiver pressure again rises.

25 It will thus be seen that valve 17 is automatically closed when a predetermined high receiver pressure is reached and it automatically opens again when a predetermined lower receiver pressure is reached. The upper and lower limits at which valve 17 is operated can be adjusted by adjusting 30 weights 45 and 56.

Owing to the method of connecting frame 12 to the face of the compressor inlet 10, this 35 frame acts as a relief valve to prevent damage to the compressor in the event of the non-return valve (not shown) provided on the delivery side of the compressor, failing to act when inlet valve 17 is closed and the 40 machine shut down. In such a case high pressure air would find its way into the low pressure casing in a centrifugal machine and possibly damage it. With the frame 12 yieldingly connected to inlet 10 as above described, with the rise of pressure on the side 45 next the compressor, the frame would be blown off its seat against the compression of the springs 15 to relieve the pressure and thus prevent the pressure in the low pressure 50 stages reaching a dangerous degree.

In accordance with the provisions of the patent statutes, I have described the principle of operation of my invention, together with the apparatus which I now consider to 55 represent the best embodiment thereof, but I desire to have it understood that the apparatus shown is only illustrative and that the invention may be carried out by other means.

What I claim as new and desire to secure 60 by Letters Patent of the United States, is:—

1. In combination, a compressor having an inlet conduit and a discharge conduit, a valve in the inlet conduit, means for causing 65 said valve to assume one of two positions when the pressure on the discharge

side of the compressor reaches certain definite adjustable limits, and means for adjusting said limits independently with respect to each other.

2. In combination, a compressor having 70 an inlet conduit and a discharge conduit, a valve in the inlet conduit, means for immediately closing said valve when the pressure on the discharge side of the compressor reaches a predetermined high value, and means for immediately opening it when the pressure reaches a predetermined low value, said means being independently adjustable with respect to each other whereby either of said pressure values may be adjusted 75 without affecting the other.

3. In combination, a compressor having 80 an inlet conduit and a discharge conduit, a valve in the inlet conduit, a movable abutment subjected to the pressure on the discharge side of the compressor for closing said valve when the pressure reaches a predetermined high value, a catch for holding it closed, and means for releasing said catch when the pressure reaches a predetermined 85 low value.

4. In combination, a compressor having 90 an inlet conduit and a discharge conduit, a valve in the inlet conduit, means for closing said valve when the pressure on the discharge side of the compressor reaches a predetermined high value, means for opening it when the pressure reaches a predetermined low value, and means for adjusting 95 the pressures at which said opening and closing means operate comprising independently adjustable weights whereby an adjustment of one pressure value may be made without affecting the other value.

5. In combination, a compressor having 100 an inlet conduit and a discharge conduit, a casing, a valve in the casing, said casing being spring held against the end of the inlet conduit, a movable abutment connected to said valve, means actuated by the pressure 105 on the discharge side of the compressor for causing the abutment to move the valve to the closed position when such pressure reaches a predetermined high value and to move such valve to the full open position 110 when such pressure falls to a predetermined low value, and means provided in conjunction with said first named means for independently adjusting either of said predetermined pressure values with respect to the 115 other whereby the valve may be caused to operate between certain pressure limits.

6. In combination, a compressor having 120 an inlet conduit and a discharge conduit, a valve in the inlet conduit, a movable abutment connected to said valve, a conduit for conveying fluid pressure to said abutment, and a valve actuated by the pressure on the discharge side of the compressor for connecting 125 said conduit to a source of fluid 130

pressure or to a region of lower pressure, whereby when the pressure on the discharge side of the compressor reaches a predetermined high value the valve in the inlet will be closed and when it reaches a predetermined low value such valve will be opened.

7. In combination, a compressor having an inlet conduit and a discharge conduit, a valve in the inlet conduit, a movable abutment connected to said valve, a conduit for conveying fluid pressure to said abutment, a valve actuated by the pressure on the discharge side of the compressor for connecting said conduit to a source of fluid pressure, a catch for holding the fluid pressure actuated valve in open position, and means for releasing said catch.

8. In combination, a compressor having an inlet conduit and a discharge conduit, a valve casing held in engagement with and forming the outer end of the inlet conduit, said valve casing being releasable therefrom automatically in the event of back pressure tending to convert the inlet conduit into a discharge conduit, a valve in said casing, means interposed between said valve and the discharge conduit to cause said valve to assume a closed position when a predetermined high pressure is reached in the discharge conduit and to cause said valve to assume an open position when the predetermined low pressure is reached in the discharge conduit, said high and low pressure limits being independently adjustable with

respect to each other through the medium 35 of sectional adjustable weights.

9. In combination, a compressor having an inlet conduit and a discharge conduit, a normally open valve in the inlet conduit, means for closing said valve when the pressure on the discharge side of said compressor reaches a predetermined high value, latch releasable means for holding it closed until said pressure reaches a predetermined low value, and means for releasing said holding means and opening the valve when the pressure reaches such predetermined low value.

10. In combination, a compressor having an inlet conduit and a discharge conduit, a valve in the inlet conduit biased toward open position, a movable abutment connected to the valve, a conduit for supplying pressure to the abutment to cause it to close the valve against the biasing force, and means for connecting said last named conduit to a source of pressure or to a region of lower pressure, said means being actuated by the pressure on the delivery side of the compressor.

In witness whereof, I have hereunto set my hand this fourteenth day of March, 1921.

R. H. COLLINGHAM.
